UNITED STATES PATENT OFFICE.

MATHIAS SMOLIK, OF PITTSBURGH, PENNSYLVANIA, ASSIGNOR OF ONE-HALF TO
FRANK KLOUSNITZER AND ONE-HALF TO KARL ARTHUR PRIMSLER, BOTH OF
PITTSBURGH, PENNSYLVANIA.

FIGURE TOY.

1,210,999.

Specification of Letters Patent.

Patented Jan. 2, 1917.

Application filed August 19, 1916. Serial No. 115,794.

To all whom it may concern:

Be it known that I, MATHIAS SMOLIK, a citizen of the United States of America, residing at Pittsburgh, county of Allegheny, 5 and State of Pennsylvania, have invented certain new and useful Improvements in Figure Toys, of which the following is a specification.

This invention relates to figure toys, and 10 has for its object to provide a device of such class, in a manner as hereinafter referred to, with a pair of miniature figures representing a pair of animals, for example goats, having means associated therewith for shifting the miniature figures to give the appearance that they are fighting each other thereby affording considerable amusement when the toy is operated.

A further object of the invention is to provide 20 a toy of the character referred to with means for creating sounds, to represent the bleats of an animal, during the operation of the toy.

Further objects of the invention are to 25 provide a figure toy which is simple in its construction, durable, amusing when used, convenient to operate, and inexpensive to manufacture.

With the foregoing and other objects in 30 view the invention consists of the novel construction, combination and arrangement of parts, as hereinafter more specifically described and illustrated in the accompanying drawings, wherein is shown an embodiment 35 of the invention, but it is to be understood that changes, variations and modifications can be resorted to which come within the scope of the claims hereunto appended.

In the drawings wherein like reference 40 characters denote corresponding parts throughout the several views; Figure 1 is an elevation, broken away, of a toy in accordance with this invention. Fig. 2 is a sectional detail.

Referring to the drawings in detail 1 denotes a casing having a partition or platform 2, to provide an upper and a closed lower compartment 3, 4, respectively. The upper compartment 3, has an open front 5, so that the antics of a pair of miniature figures 6, 7, can be seen. The figures 6, 7, are 50 preferably animals, as shown by way of example, a pair of goats. Each of the figures

6, 7, have the legs 8, loosely connected with the body thereof. 55

The figures 6, 7, are suspended within the compartment 3 on the upper ends of vertically disposed springs or resilient members of ogee curvature. The spring or resilient member for the figure 6 is indicated at 10, 60 and the spring or resilient member for the figure 7 is indicated at 11. The springs 10, 11, are of the same contour and one is arranged parallel to the other, that is to say they are not oppositely disposed. 65

The partition 2 is formed with a pair of elongated rectangular slots 12, 13, which are disposed longitudinally of the partition 2, and arranged in longitudinal alinement. Extending across the slot 12, near the outer end thereof, is a guide bar 14, against which rides the spring 10, and extending across the slot 13 approximately centrally thereof is a guide bar 15, against which rides the spring 11. 70

The springs 10, 11, extend down into the compartment 4 and have their lower ends connected, as at 15^a, to an operating lever 16, which is pivotally connected, as at 17, to a support 18, arranged within the compartment 4. The lever 16 projects outwardly through a vertical slot 19 formed in one side of the casing to enable the convenient shifting of the lever on its pivot to reciprocate the springs 10, 11, to actuate the figures 6, 7, 80 85 to give the appearance that they are fighting each other.

Arranged upon the bottom of the compartment 4 is a sounding device 20 engaged and operated by the handle end of the lever 90 16 when said end is lowered. The sounding device is of the ordinary type, bellows and reed or whistle, employed in sounding toys.

When the lever 16, is operated, the springs 10, 11, riding against the guide bars 14, 15, 95 cause the shifting of the figures 6, 7, so one will appear as attacking the other causing by their antics considerable amusement.

What I claim is:—

1. A figure toy comprising a casing provided with a partition having a pair of slots, resilient members of ogee curvature extending down through said slots, miniature figures mounted on the upper ends of said members, an oscillatory lever having said members connected therewith and adapted 100 105

- when operated to reciprocate said members, and guide bars extending across said slots and against which ride said members when reciprocated.
5. 2. A figure toy comprising a casing provided with a partition having a pair of slots, resilient members of ogee curvature extending down through said slots, miniature figures mounted on the upper ends of said members, an oscillatory lever having said members connected therewith and adapted when operated to reciprocate said members, and guide bars extending across said slots and against which ride said members when reciprocated.
- 10 15 10. 3. A figure toy comprising a platform provided with a pair of rectangular slots, curved resilient members extending down through said slots, miniature figures mounted on the upper ends of said members, an oscillatory lever having said members connected therewith and adapted when operated to reciprocate said members to shift said miniature figures, and guide bars extending across said slots and against which ride said members when reciprocated.
- 15 20 25 4. A figure toy comprising a platform 30 provided with a pair of rectangular slots, curved resilient members extending down through said slots, miniature figures mounted on the upper ends of said members, an oscillatory lever having said members 35 connected therewith and adapted when operated to reciprocate said members to shift said miniature figures, and guide bars extending across said slots and against which ride said members when reciprocated, one of 40 said guides positioned near the outer end of its respective slot and the other guide bar arranged approximately centrally of its respective slot.

In testimony whereof I affix my signature 45
in the presence of two witnesses.

MATHIAS SMOLIK.
